UNITED STATES PATENT OFFICE.

WILLIAM CASTANIE, OF PORT ARTHUR, TEXAS.

CHUCK.

1,401,312.

Specification of Letters Patent. Patented Dec. 27, 1921.

Application filed December 27, 1920. Serial No. 433,366.

To all whom it may concern:

Be it known that I, WILLIAM CASTANIE, a citizen of the United States, residing at Port Arthur, in the county of Jefferson and State 5 of Texas, have invented a new and useful Chuck, of which the following is a specification.

This invention relates to chucks or pipe supports for holding pipes or the like while 10 the same are being cut or threaded.

The primary object of the invention is to provide a device of this character which will securely clamp the pipe under operation, in a manner to prevent movement thereof.

15 A further object of the invention is to provide movable jaws which may be readily and easily moved into clamping relation with the pipe, the operating means being constructed to lock the jaws in their clamping 20 positions.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

30 Referring to the drawings:—

Figure 1 is a front elevational view of a chuck constructed in accordance with the present invention.

35 Fig. 2 is a side elevational view of the same.

Fig. 3 is a front elevational view of the chuck, the cover plate thereof being removed.

40 Fig. 4 is a sectional view taken on line 4—4 of Fig. 3.

Referring to the drawings in detail, the reference character 5 designates the body of the chuck which includes the circular head 6 and the stem 7, the circular head being 45 provided with a flange 8 to accommodate the jaw carrying ring 9. The head 6 is cut away to provide an enlargement 10, which enlargement is cut away to provide the clearances 11 designed to accommodate the clamp 50 arms 12 which have laterally extending portions 13 providing jaws.

The jaw carrying ring carries the plates 14 on the opposite sides thereof, which plates provide supports for the outer ends of the 55 clamping arms 12 there being provided pivot pins 15 for connecting the clamp arms to the

plates 14 to permit of pivotal movement of the clamp arms with respect thereto.

The ring 9 is formed of opposed sections pivotally connected as at 16, the opposite 60 ends of the section being connected by the link 17 and lever 18, the link 17 being shown as having pivotal connection with the boss 19, while the lever 18 has pivotal connection with the boss 20 forming a part of the opposed 65 section. The link 17 also has connection with the lever 18 as at 21, so that movement of the lever 18 to a position as shown by Fig. 3 of the drawings, moves the sections of the ring toward each other to cause a relative 70 movement of the clamping jaws to clamp an article.

When the lever is moved in the opposite direction, the sections of the ring are moved with respect to each other to cause the jaws 75 to move out of clamping relation with each other to release the pipe or article under operation.

Positioned on the clamp arms 12, is a circular member 22 which carries lugs 23 adapted 80 to be positioned between the clamp arms to hold the same in their proper relation with respect to the walls of the clearances 11.

In order that the clamp arms will be supported in proper position within the head, a 85 cover plate 24 is provided, which cover plate is secured to the head, as by means of the screws 25 which pass through suitable openings provided in the plate and head. This plate 24 is provided with a central opening 90 adapted to permit the jaws of the clamp to pass therethrough and grip an article under operation.

It is believed that in view of the foregoing description, a further detail description as 95 to the operation of the device is unnecessary.

Having thus described the invention, what is claimed as new is:—

1. In a pipe clamping device, a head, said head being cut away to provide clearances, a 100 clamp arm supporting ring secured to the head, clamp arms carried by the ring and having jaws formed at the free ends thereof, said ring being formed of opposed sections, means for connecting the sections to permit the sections to be moved with respect to each other, and said sections adapted to move the clamp arms and jaws toward and away from each other.

2. In a pipe clamping device, a head, said 110 head being cut away to provide clearances, clamp arms positioned between the clear-

ances, a sectional ring member having connection with the clamp arms, jaws formed at one end of each clamp arm, means for moving the sections of the ring to move the clamp arms to cause the jaws to move with respect to each other, and a cover plate having connection with the head for restricting movement of the clamp arms.

3. In a pipe clamping device, a head, a sectional ring supported by the head, the sections being pivotally connected, clamp arms pivotally connected to the ring, said clamp arms having jaws formed at their free ends,

means disposed between the clamp arms for holding the same in spaced relation with each other, and means for connecting the opposite ends of the sectional ring for moving the arms with respect to each other.

In testimony that I claim the foregoing as my own, I have hereto affixed my signature in the presence of two witnesses.

WILLIAM CASTANIE.
